UNITED STATES PATENT OFFICE.

SAMUEL GOODMAN, OF CHICAGO, ILLINOIS.

WINDOW.

Application filed July 5, 1923. Serial No. 649,659.

To all whom it may concern:

Be it known that I, SAMUEL GOODMAN, a citizen of the United States, residing at Chicago, in the county of Cook and State of Illinois, have invented new and useful Improvements in Windows, of which the following is a specification.

This invention relates to windows or the like and more particularly to a window provided with upper and lower sashes which are capable of vertical sliding movement within the window frame and also inward lateral swinging movement, and an object is to provide a window of this character wherein the sashes are readily removable and replaceable and adapted to be readily cleaned at the inside of the building.

Another object of this invention is to provide a window wherein the sashes may be raised or lowered in vertical direction and retained at any desired position.

A further object is to provide a novel form of window wherein the sashes may be manipulated to any desired vertical or horizontal swinging position.

A still further object of the invention is to provide the window with means for maintaining the lower sash in slightly elevated position to provide for the ready inward swinging of the lower sash without necessitating the raising of the window in vertical direction.

Another object of this invention is to provide a window which employs no ropes, weights, and the like, and I hereby reserve the right to make such variations and alterations therein from time to time to meet the exigencies of the case without departing from the spirit of the invention or conflicting with the scope of the claims.

These and other objects will more fully appear in the following specification, the subject matter of the claims, and as disclosed in the several views of the accompanying drawings, in which:

Figure 1 is an elevation of the window when viewing the same from the inside of the room.

Fig. 2 is a transverse sectional view taken on line 2—2 of Fig. 1 looking in the direction of the arrows showing the sashes in dotted line position that the same assume when swung inwardly;

Fig. 3 is a vertical sectional view on line 3—3 of Fig. 1 looking in the direction of the arrows;

Fig. 4 is a similar view to Fig. 1 the sash holding strips being omitted to illustrate other details.

Fig. 5 is a detail sectional view of one of the lower corners of the sashes showing part of the co-operating means for retaining the sashes in vertical position;

Fig. 6 is a view of the left-hand end of the lower sash showing the means provided for the vertical and swinging movements of the sash, the right-hand end of the upper sash, being correspondingly constructed.

Fig. 7 is a side elevation, partly in section, of one of the hinge members for the lower sash.

Referring to the drawings, 1 represents the sides of the window frame, 2 the lintel and 3 the sill. At the outer sides of the side members 1 of the frame are the outer retaining strips 4 and also upon the same sides of the frame members and just inwardly of the retaining members 4 are metal guide strips 5. These strips 5 extend from the lintel 2 downwardly, and terminate in proximity to the meeting rails of the sashes; and from there down to the sill are spaced guide blocks 6.

The upper sash 7 is provided with hinge plates 49 having apertured ears 9, these hinge plates being secured at the respective upper and lower corners at the left-hand edge of the sash 7. The lower hinge member 49 of the sash 7 is secured thereon just above the housing 10 of a spring latch member 11 more clearly shown in Fig. 5 of the drawings. This latch 11 engages a rack bar 12 secured at the lower side portion of the frame 1 for retaining the upper sash 7 in its vertical adjusted positions. There is also secured upon this frame rail 1 the hinge pintle 13 positioned thereon just above the uppermost position of the lower hinge member 49 and also secured upon the same frame rail 1 is a similar hinge pintle 14 in proximity to the sill 3 of the window frame. Upon the lower sash 8 at the upper and lower corners at the right-hand end are the hinge members 15 provided with the ears 16 for receiving the hinge pintles 17 of the leaf members 18 secured upon the opposite inner side of the right-hand member 1 of the window frame and surrounding the pintles 17 are the compression springs 19 upon which are yieldingly supported the ears 16 of the hinge members 15. Secured upon the respective lower corners of the sash frame 8 are the

latch members 20 which are similar to the latch member 10 of the upper sash 7 and these latches 20 are adapted to engage the respective rack bars 21 secured upon the inner 5 opposing faces of the frame members 1, whereby to position the lower sash 8 at any desired point of vertical elevation between the lintel 2 and the sill 3.

The end rails of the sashes 7 and 8 at their 10 respective hinged sides are each provided with a continuous groove from the lower rail to the upper rail thereof for guiding the respective sashes in their vertical sliding directions. However, the end rails at the free 15 ends of the sashes 7 and 8 are similarly grooved in the manner shown at 22 in Fig. 6 with the exception that these ends are additionally provided with laterally extending channels 23, these channels, it being understood, 20 opening at one side edge of the respective ends and extending inwardly until the same intersect the vertical groove 22. This view shown in Fig. 6 being identical with the formation of the free end of the lower 25 sash 8, it being understood, of course, that the groove 22 and channels 23 at the free end of the upper sash 7 are correspondingly formed.

When it is desirous to swing the sashes inwardly, the lower sash 8 is brought to such 30 position that the ears 16 rest on springs 19 and then may now be readily swung inwardly in view of the fact that the channels 23 will permit this end of the sash to readily 35 pass the guide blocks 6 on the window frame and also due to the compression springs 19 elevating the lower edge of the bottom rail of the sash 8 sufficiently to permit this rail to pass over the top of the sill 3 of the frame, 40 whereby the lower sash may swing to the position shown in dotted lines in Fig. 2. Subsequently the upper sash 7 will also be lowered until the upper ear 9 of the upper hinge plate 49 engages the hinge pintle 13 substantially 45 midway of the ends of the window frame and the lower ear 9 engages the hinge pintle 14 positioned adjacent the sill 3 of the window frame, so that, when the upper sash 7 has assumed this position 50 the free end thereof which is formed in the manner hereinbefore described is now free to be swung inwardly past the guide blocks 6, to the position shown in dotted lines in Fig. 2.

The window hereinbefore described is also 55 provided with the sash holding strips 24 hingedly secured to the inwardly extending portions of the side members 1 of the window frame by the hinges 25, the strips 24 serving to guard the inner sash against accidental 60 swinging motion, and being also provided with the securing latches 26 adjacent their free overlapping ends 27. In other words the sash holding strips 24 are swung 65 into engagement with the inner side of the

inner sash and thereby hold the inner sash in position.

The sash frames are also provided with any preferred form of lifting handle 28 and any desired form of locking members 29 at the respective meeting rails of the sashes.

From the foregoing description of my invention, it is manifestly clear that I am enabled to produce a window construction that is neat in appearance, and one which provides a combined sliding and swinging sash construction to thereby eliminate the use of the customary window cords and sash weights and which at the same time provides for the ready removal, replacing, as well as providing for the ready and safe cleaning of the windows.

Having thus described my invention, what I claim as new and desire to secure by Letters Patent is:

1. A window comprising a frame, a sash having one vertical side hinged to the frame and the other vertical side of the sash being formed with a longitudinal groove and lateral branches communicating with the groove, guide blocks carried by the frame and received in said groove and adapted to be received in said lateral branches during the swinging of the sash to close or open position.

2. A window comprising a frame, a sash having one vertical side hinged to the frame and the other vertical side of the sash being formed with a longitudinal groove and lateral branches communicating with the groove, guide blocks carried by the frame and received in said groove and adapted to be received in said lateral branches during the swinging of the sash to closed or open position, and sash holding strips hinged to said frame for movement about vertical axes and adapted to engage the inner surface of the sash to hold the sash in position.

3. A window comprising a frame, a sash having one vertical side hinged to the frame and the other vertical side of the sash being formed with a longitudinal groove and lateral branches communicating with the groove, guide blocks carried by the frame and received in said groove and adapted to be received in said lateral branches during the swinging of the sash to closed or open position, and sash holding strips hinged to said frame for movement about vertical axes and adapted to engage the inner surface of the sash to hold the sash in position, said frame being provided with a sill, and spring means to urge the sash upwardly to clear said sill.

4. A window comprising a frame, a sash arranged in the frame and having one vertical edge portion formed with upper and lower hinged plates and the other vertical side of the sash being formed with a vertical groove, said sash also being provided

with lateral branches communicating with said groove, pintles carried by the frame and adapted for connection with the hinge plates, said frame being provided with a sill, springs 5 mounted on said pintles and engaging said hinge plates for urging the sash above the plane of the sill, and guide blocks carried by the frame and received in said groove, the lateral branches which communicate with 10 said groove forming a means whereby the sash may be swung upon its hinge to open or closed position.

5. A window comprising a frame, a sash arranged in the frame and having one vertical edge portion formed with upper and 15 lower hinged plates and the other vertical side of the sash being formed with a vertical groove, said sash also being provided

with lateral branches communicating with said groove, pintles carried by the frame and adapted for connection with the hinge plates, said frame being provided with a sill, springs 20 mounted on said pintles and engaging said hinge plates for urging the sash above the plane of the sill, guide blocks carried by the frame and received in said groove, the lateral branches which communicate with 25 said groove forming a means whereby the sash may be swung upon its hinge to open or closed position, and sash 30 retaining strips vertically hinged to said frame and engaging the inner side of said sash.

In testimony whereof I affix my signature.

SAMUEL GOODMAN.
